UNITED STATES PATENT OFFICE.

FRANK KANE, OF TACONY, PENNSYLVANIA.

DIAPHRAGM FOR TALKING-MACHINES.

960,021.

Specification of Letters Patent. Patented May 31, 1910.

Application filed July 23, 1907, Serial No. 385,203. Renewed January 10, 1910. Serial No. 537,339.

To all whom it may concern:

Be it known that I, FRANK KANE, a citizen of the United States, residing at Tacony, county of Philadelphia, and State 5 of Pennsylvania, have invented a certain new and useful Improvement in Diaphragms for Talking-Machines, of which the following is a specification.

My invention relates to a new and useful 10 improvement in diaphragms for talking machines, and has for its object to so construct a diaphragm as to enable it to reproduce with greater accuracy the various sounds, such as singing, talking and the tones of all 15 kinds of musical instruments and to prevent the harsh metallic sound heretofore incident to the reproduction by such machines.

With these ends in view, this invention 20 consists in the details of construction and combination of elements hereinafter set forth and then specifically designated by the claim.

In order that those skilled in the art to 25 which this invention appertains may understand how to make and use the same, I will describe its construction in detail, referring by letter to the accompanying drawing forming a part of this specification, in which—

Figure 1 is a plan view of my improved 30 diaphragm, and Fig. 2, a central section thereof.

In carrying out my invention as here embodied I make a diaphragm of a composition of metal consisting of two parts of copper and one part of spelter, the horizontal 35 portion A of which varies in thickness from its outer diameter which is very thin to the central or cupped portion B where it is much thicker and by thus varying the thickness of the diaphragm I provide for the reproduction 40 of various tones and volume of sound,

and the cupped portion B acts as a reservoir for the sound waves to increase their volume.

I am aware that diaphragms have been made of copper, but in practice such diaphragms give out a harsh metallic sound, and while fairly reproducing the sound waves of a drum or heavy wind instruments it does not accurately produce the sounds of a 45 stringed instrument, such as a banjo, nor does it accurately reproduce the various 50 tones of the human voice, whereas my diaphragm will accurately reproduce all of the various sounds separately or at the same time making it especially applicable to the reproduction of the sounds of an orchestra 55 together with singing.

One of the advantages of the concave portion B of the diaphragm is that it houses the sound vibrations from the record, thus giving a clearer tone to the sounds issuing 60 from the horn, and it also strengthens the diaphragm, and as the latter is made of metal it is very durable.

Having thus fully described my invention, what I claim as new and useful, is—

A diaphragm composed of a central cupped portion of uniform thickness and a horizontal disk like portion being of greatest thickness at the periphery of said cupped portion and thence gradually decreasing in 65 thickness and tapering to the periphery of said disk-like portion which is of least and wafer like thickness.

In testimony whereof, I have hereunto affixed my signature in the presence of two 70 75 subscribing witnesses.

FRANK KANE.
